POR TABLE ELECTRICAL APPARATUS

Charles Vance Dame, Lanark, Ill.

Application April 29, 1931. Serial No. 533,854

4 Claims. (Cl. 224—5)

My invention relates to improvements in portable electrical apparatus, and it consists in the combinations, constructions, and arrangements herein described and claimed.

and bottom plates 3 and 4, respectively, together with the casing 2, may be held together as a unit. As shown in Figure 2 link members 8 are formed for receiving the inner adjacent rods 5 of the adjacent casings, said link members being slidably mounted on said rods. Connected with the link member 8 is a spring member 9 having portions formed for receiving the outer and adjacent rod members 5 of the containers 1 and slideable with respect thereto. The spring members 9 tend to hold the containers in an aligned position.

5 An object of my invention is to provide a portable electrical apparatus having novel means whereby the batteries from which said apparatus obtains its power may be easily transported.

The extreme end rods 5 of the end containers are provided with bracket members 11 which are formed for receiving the rods and slidably with respect thereto. The bracket members 11 are connected with a belt member 12 which is adapted

10. A further object is to provide novel means whereby several batteries may be carried on the body of a person with a minimum of discomfort to the person.

for being disposed around the body of the wearer. A belt member 12 has the ends thereof connected with the brackets 11 and is adapted for being disposed around the waist of the wearer whereby the containers may be held in engagement there-

A further object is to provide novel means whereby batteries may be carried for energizing an electrical device, said means being adapted for being held in fixed engagement with the body of the wearer.

the containers may be held in engagement therewith. The top plate member of each of the containers is provided with a T-shaped neck portion 13. The cover plate is also provided with insulated contacts 14 adapted for engaging the

Other objects and advantages will appear in the following specification, and the novel features of the invention will be particularly pointed out in the appended claims.

terminals 15 of a battery 34 when said battery is disposed within the container. As shown in Figure 5 the bottom plate 4, if so desired, may be provided with a contact element 16 which engages

My invention is illustrated in the accompanying drawing, forming part of this application, in which

the metal casing of the battery which may be used in lieu of an insulated contact connected with the top plate for engaging the terminal associated with the metal battery casing. An end 17 of the T-shaped neck 13 is provided with a

battery terminal and the contact 18 is in electrical communication with the other of the battery terminals. The contact 18 is also in electrical communication with the contact 21. The extreme rod members 5 of the end containers are

portion of one of the battery containers, Figure 4 is a section taken along the line 4-4 of Figure 3.

provided with looped members 23 with which the ends of a sling 24 are connected. The sling 24 is provided with pockets 25 for receiving the handle 26 of an electric lamp 27. The end 17' of the neck 12 connected with one of the ends of the

neck 13 connected with one of the end containers is provided with a plug 28 for providing communication between the contacts 21 and 22. 103

45 Figure 7 is a detail diagrammatic view showing the circuit.

with the neck of the other end container are connected with the light 27. A switch 29 is disposed on the bottom cover plate of one of the containers and included in the electrical circuit as shown in Figure 7 whereby the light 27 may be actuated at will. The faces of the containers 1 positioned adjacent the body of the wearer are provided with pads 33 which serve as a cushion between the containers and the wearer's body. It will be seen by referring to Figure 6 that the conductors or wires 35 which provide communication between the batteries and the light are coiled so that the light may be removed from the pocket in order that the operator may hold it in some other location than in the pocket.

The shoulder sling 24 and the belt member 12 are provided with buckles or similar means not shown whereby they may be adjusted.

From the foregoing description of the various parts of the device, the operation thereof may be readily understood. The shoulder sling 24 is first thrown over the shoulder of the wearer and is adjusted so that the containers will be properly positioned on the side of the wearer. The sling is slung over the shoulder so that the light 27 will be positioned at the front of the wearer. The belt 12 is then tightened for drawing the containers into engagement with the body. It will thus be seen that the batteries within the containers may be carried with little or no inconvenience to the wearer. It will also be seen that the switch 29 may be readily actuated, even while the wearer is carrying articles in his hands because of its convenient position, from the bottom of one of the containers.

When it is desired that the light be directed to some particular location, the lamp 27 may be removed from its pocket and utilized as is an ordinary flashlight. It will also be readily seen that other electrical devices might be used in lieu of the lamp 27, such as a telephone transmitter which might be desired if applicant's invention should be used as army equipment. The number of articles which it is desired to use may be varied by merely removing the proper nuts 7 whereby the respective threaded rods 5 may be removed from engagement with the proper link members 8 and the spring means 9 thereby permitting adjacent containers to be disconnected. In like manner the bracket members may be removed

from their respective rods 5 and disposed on the rods of other containers.

I claim:

1. A device adapted to be worn around the body comprising a group of containers each contiguous pair of which is provided with an interposed hinge adjacent the body side thereof for flexibly connecting the same, a spring disposed between adjacent sides of each pair of said containers and having its intermediate portion secured to the respective hinge and its ends extended forwardly and secured to said containers adjacent the free outer sides thereof, and supporting means for said containers secured to the end members of said group. 80

2. A device adapted to be worn around the body comprising a group of rectangular containers each having a removable end closure member, bolts adjacent the corners of the said containers for securing said closures in position, a hinge secured to a bolt of the body side of each of two adjacent containers for flexibly securing the same together, a spring secured intermediate its ends to each hinge and to the bolts adjacent the forward corners of the respective containers for controlling the flexing movement of said containers, and means secured to the end members of said group for supporting the same. 85

3. A portable electric device adapted to be worn around the body comprising a group of dry cell 105 containers having removable end closure members, a plurality of bolts for each container for securing said closure members in position, a hinge secured to a bolt of each of two adjacent containers on the body side thereof for flexibly securing 110 the same together, springs each secured at the intermediate portions thereof to one of said hinges and at its ends to other bolts of said adjacent containers for controlling the flexing movement thereof, and supporting means for said 115 group of containers. 100

4. Apparatus adapted to be worn around the body comprising a belt, a group of containers secured thereto, a hinge flexibly connecting adjacent containers adjacent the body side thereof, 120 and a spring secured to each hinge and to forward portions of each of the respective containers for controlling the flexing action of the same. 125
